(57) **CLAIM**

The ornamental design for a concealed carry vest, as shown and described.

DESCRIPTION

FIG. 1 is a left isometric view of a concealed carry vest according to a first embodiment.

FIG. 2 is a left isometric view of the concealed carry vest with the holster compartment open.

FIG. 3 is a left isometric view of the concealed carry vest with the holster compartment open and an in-waistband holster secured withing the holster compartment.

FIG. 4 is a front view of the concealed carry vest.

FIG. 5 is a front view of the concealed carry vest with the holster compartment open.

FIG. 6 is a front view of the concealed carry vest with the holster compartment open and an in-waistband holster secured withing the holster compartment.

FIG. 7 is a back view of the concealed carry vest.

FIG. 8 is a left view of the concealed carry vest.

FIG. 9 is a left view of the concealed carry vest with the holster compartment open.

FIG. 10 is a right view of the concealed carry vest.

FIG. 11 is a top view of the concealed carry vest.

FIG. 12 is a bottom view of the concealed carry vest.

FIG. 13 is a right isometric view of the concealed carry vest according to a second embodiment.

FIG. 14 is a right isometric view of the concealed carry vest of FIG. 13 with the holster compartment open.

FIG. 15 is a right isometric view of the concealed carry vest of FIG. 13 with the holster compartment open and an in-waistband holster secured withing the holster compartment.

FIG. 16 is a front view of the concealed carry vest of FIG. 13.

FIG. 17 is a front view of the concealed carry vest of FIG. 13 with the holster compartment open.

FIG. 18 is a front view of the concealed carry vest of FIG. 13 with the holster compartment open and an in-waistband holster secured withing the holster compartment.

(Continued)

FIG. 19 is a back view of the concealed carry vest of FIG. 13.

FIG. 20 is a left view of the concealed carry vest of FIG. 13. FIG. 21 is a right view of the concealed carry vest of FIG. 13.

FIG. 22 is a right view of the concealed carry vest of FIG. 13 with the holster compartment open.

FIG. 23 is a top view of the concealed carry vest of FIG. 13; and,

FIG. 24 is a bottom view of the concealed carry vest of FIG. 13.

The broken lines shown within the drawings are included for the purpose of illustrating portions of the concealed carry vest that form no part of the claimed design.
